OVERSHOE FOR SKATES

Adolf Kutchera, Bismarck, N. Dak.

Application March 23, 1933, Serial No. 662,362

2 Claims. (Cl. 36—7.5)

This invention relates to skates and more particularly to a means for the protection of ice skates.

An object of this invention is to provide what might be called an overshoe or protecting means for the blade of an ice skate so that the skate may be attached to the shoe at a point remote from the ice and the person may walk to the ice without injuring the keenness of the blade of the skate.

Another object of this invention is to provide an overshoe or protecting means which is relatively strong and at the same time light in construction so that it can be quickly attached or detached from the shoe and about the skate.

A further object of this invention is to provide a skate protecting means which is so constructed that the person wearing the skate will not be required, where skates attached to shoes are used, to carry an extra pair of shoes along and take off the conventional shoe at a point closely adjacent to the skating rink and thereby endanger his health on account of the temperature changes.

The above and various other objects and advantages of this invention will in part be described and in part be understood from the following detailed description of the present preferred embodiment, the same being illustrated in the accompanying drawings wherein:—

Figure 1 is a detail side elevation of a shoe having a skate attached thereto and an overshoe or protecting means constructed according to the preferred embodiment of this invention attached to the shoe about the skate.

Figure 2 is a top plan view partly broken away of the overshoe or skate protecting means.

Figure 3 is a longitudinal section taken on the line 3—3 of Figure 1.

Figure 4 is a fragmentary sectional view taken on the line 4—4 of Figure 1.

Figure 5 is a fragmentary sectional view taken on the line 5—5 of Figure 1.

Referring to the drawings wherein like characters of reference designate corresponding parts throughout the several views, the letter S designates generally a shoe of conventional construction provided with a sole or bottom 10. A skate, generally designated as 11, is engaged with the bottom of the shoe S and, in the present instance, this skate 11 comprises a front sole engaging plate 12, a rear heel engaging plate 13, each of which plates is attached to the sole or bottom 10 of the shoe S by means of rivets or securing members 14 or the like. A blade or

runner 15 is attached to the bottom plates 12 and 13 by means of a frame structure including a front post 16 and a rear post 17 and a longitudinally extending tubular member 18.

This skate is a conventional skate structure and I, of course, do not wish to be limited to any particular type of skate or shoe to which the device hereinafter described may be attached, and the skate and shoe is used only diagrammatically or as an example of one type of skate and shoe with which the device hereinafter described may be engaged.

In order to protect the runner or blade 15 of the skate when the person is walking on the ground or on any surface which might injure the keen edges of the runner, I have provided an overshoe or protecting means comprising a front frame structure 19, a rear frame structure 20 and an intermediate frame structure 21. This front frame structure comprises a top plate 22, provided with depending marginal flanges 23 and having a substantially U-shaped slot or opening 24 in the center thereof.

A substantially U-shaped upright member or standard 25 is secured to the plate 22, and this support or standard 25 has the body thereof cut out, as at 26, to provide a substantially web-like side wall so as to increase the lightness of the support or standard while maintaining a relatively rigid standard.

A bottom plate 27 which is longitudinally curved, after the manner of the sole of a shoe, is secured to the bottom 28 of the standard 25, and this sole plate 27 is provided with upturned marginal flanges 29. A sole 30 of desired composition such as rubber, leather or the like, is attached as by rivets or securing members 31 to the sole plate 27.

The bight or front of the U-shaped support or frame 25 is provided with a recess or opening 32 to receive the forward end of the blade or runner 15 which may project forwardly and beyond the front member 19. Preferably, the front post or support 33 of the skate 11 extends between the marginal flange 23 and the front of the plate 22, so that this marginal flange 23 will act to prevent movement of the front of the overshoe relative to the skate 11 and shoe S.

The rear frame or overshoe structure 20 comprises a substantially U-shaped vertical frame structure or supporting means 34 provided with a heel plate 35 having a slot or opening 36, and the rear or bight of the rear frame member 20 is provided with a vertical opening or passage 37 to receive the rear of the runner or blade 15.

The rear frame structure 34 projects upwardly above the heel plate 35, as at 38, and this upwardly projecting portion is provided with a slot 39 on opposite sides to receive securing means in the form of a strap 40, one end of the strap 40 being disposed in one slot or opening 39 and the other end being disposed in the other or opposing opening 39.

A bottom plate 41 is integral with the side walls 10 34 of the rear frame structure 20, and the side walls 34 are also cut out, as at 52, so as to lighten the weight of the rear frame structure 20. A heel 42 is attached as by rivets or securing members 43 to the bottom plate 41 of the rear 15 frame, and this heel 42 coacts with the sole 30 in providing a means to facilitate the walking of the individual when the frames 19 and 20 are attached to the shoe and skate. The strap 40 is adapted to be engaged about the shoe S, as 20 shown in Figure 1, the strap engaging about the ankle and instep of the shoe.

The intermediate frame 21 includes a substantially U-shaped member having vertical sides 44 and a bottom 45. This member 21 is 25 provided on each side thereof with elongated slots 46 and 47 and in like manner, the front frame 25 is provided with an elongated slot 48 which is adapted to register with the slot 46 and through which a bolt or securing member 49 is 30 adapted to extend so that the two frame members 19 and 21 can be adjusted one relative to the other.

The frame 21 telescopes into the frame 19 and the rear of this frame 21 telescopes into the 35 rear frame 20, and the rear frame 20 is provided with slots 50 on each side thereof which are adapted to register with the slots 47 and through which a bolt or securing member 51 is 40 adapted to pass so that the rear frame 20 can be secured in a fixed adjusted position relative to the forward frame 19.

While I have shown the two frames 19 and 20 adjusted relative to each other by means of the intermediate frame 21, I do not wish to be limited to this particular construction as, if desired, other means may be used to hold these two frames relative to each other.

In the use of this overshoe or skate protecting means, the two frames 19 and 20 are first 50 adjusted relative to each other by means of the bolts 49 and 51 so that the flange 23 will engage the forward end of the skate 11 and the heel portions 38 will engage the heel of the shoe S. When these two frames have been suitably 55 adjusted, the bolts 49 and 51 can be tightened so that the frames 19 and 20 will not move relative to each other. The skate 11 with the shoe S attached thereto can then be placed within this overshoe by first projecting the forward end 33 60 of the skate into the opening 32 and then lowering the skate with the runner 15 projecting beyond the rear frame 20, the runner passing downwardly in a vertical movement through the slot 36 of the rear frame 20 and downwardly into the

slot 37 in the bight of the rear frame member 34. The strap 40 can then be tightened about the instep or ankle of the shoe S, and the overshoe will then be firmly but removably attached to the shoe S and about the skate 11.

It will, therefore, be obvious that the skater 80 may apply the skate 11 to the shoe S where the skate 11 is of a removable type and then attach the overshoe hereinbefore described to the shoe and about the skate and this may be done in a warm room so that it will not be necessary for the skater to change shoes outdoors. Upon arriving at the skating rink, the overshoe may be 85 readily detached by merely loosening the strap 40 and raising the shoe S and the skate 11 vertically and out of the overshoe structure. The overshoe structure can be replaced at the skating rink, as hereinbefore described, without removing or changing shoes and the person can then walk upon the ground or other hard surfaces without 90 injuring the blade or runner 15 as this blade is suspended within the frames 19, 20 and 21 out of engagement with the bottoms of these frames.

It is, of course, understood that various 95 changes and modifications may be made in the details of construction and design of the above 100 specifically described embodiment of this invention without departing from the spirit thereof, such changes and modifications being restricted only by the scope of the following claims.

What is claimed is:—

1. A skate protecting means comprising a frame structure including front and rear members each of said members having a substantially vertically disposed supporting structure, a bottom secured to the supporting structure, a slotted top secured to the top of the supporting structure, the slot in the top of one of the members opening through each end of the top and the slot in the top of the other of the members terminating inwardly of the adjacent end of the member, and attaching means for attaching the device to a shoe, said skate being suspended within the front and rear members intermediate the top and bottom of the members.

2. A skate protecting means comprising a frame structure including front and rear frame members, an intermediate frame member telescoping each of said members, means for adjustably securing the front and rear frame members to said intermediate member, said front and rear members having a slotted top secured thereto for engagement with the sole of a shoe, the slot of one of the frame members extending entirely through the member and dividing said one member into two parts, the slot in the other frame member terminating inwardly of one end of the member, a strap secured to one of the frame members, and means integral with the other of the frame members and coacting with the strap to hold the frame structure against movement relative to a shoe.

ADOLF KUTCHERA.
